SOCKET WRENCH STAND

Clarissa E. Caird, Santa Rosa, Calif.

Application January 14, 1955, Serial No. 33,982

Term of patent 14 years

(Cl. D80—9)

Fig. 1.

Fig. 2.

Fig. 3.

Fig. 4.

Fig. 5.

Fig. 6.

To all whom it may concern:

Be it known that I, Clarissa E. Caird, a citizen of the United States, residing at Santa Rosa, county of Sonoma, California, have invented a new, original, and ornamental Design for a Socket Wrench Stand, of which the following is a specification, reference being had to the accompanying drawing, forming part thereof.

Fig. 1 is a top plan view of a socket wrench stand showing my new design.

Fig. 2 is a left-hand side view.

Fig. 3 is a front view.

Fig. 4 is a right-hand side view.

Fig. 5 is a rear view, and

Fig. 6 is a bottom plan view.

I claim:

The ornamental design for a socket wrench stand, as shown.
